UNITED STATES PATENT OFFICE.

OSCAR D. GIBBS, OF SPOKANE, WASHINGTON.

BOX-LIDDING MACHINE.

1,111,894.

Specification of Letters Patent. Patented Sept. 29, 1914.

Application filed February 2, 1914. Serial No. 816,040.

To all whom it may concern:

Be it known that I, OSCAR D. GIBBS, a citizen of the United States, residing at Spokane, in the county of Spokane and 5 State of Washington, have invented new and useful Improvements in Box-Lidding Machines, of which the following is a specification.

This invention relates to improvements in 10 box lidding machines and one of the objects is to provide a machine in which a plurality of lids may be stored or carried by magazine and successfully and practically continuously supplied as boxes to be lidded 15 are successfully positioned.

A further object is to provide a carriage on which the magazine and the box to be lidded are disposed, the carriage being shiftable into either of two positions to locate 20 the magazine in a supply position or the box in a position to be lidded, means being provided for elevating the carriage to an operative position either to locate a lid or apply a lid to the box.

25 Other features of novelty will be more fully described in connection with the accompanying drawings and will be more particularly pointed out in and by the appended claims.

30 In the drawings: Figure 1 is a perspective view of a machine embodying one form of my invention. Fig. 2 is a view in front elevation. Fig. 3 is a view in side elevation. Fig. 4 is a view in front elevation, similar 35 to Fig. 2, but showing the parts in a different position. Fig. 5 is a view similar to Fig. 3, showing the machine in a different position. Fig. 6 is a view in plan elevation of a lid suspender device. Fig. 7 is a sectional view on line 7—7 of Fig. 6. Fig. 8 is a sectional view on line 8—8 of Fig. 4. Fig. 9 is a perspective view of a portion of a treadle mechanism.

45 Like characters of reference designate similar parts throughout the different figures of the drawings.

As illustrated, my invention includes a frame comprising uprights 1 mounted upon base frame members 2 and tied by transverse frame members 3. At their upper 50 ends, the frame uprights 1 are connected by top tie members 4 and intermediate of their ends said uprights are connected by side and end timbers 5 and 6.

55 The upright frame members 1 form guides for a carriage which is not only shiftable

horizontally but which is designed to be elevated in either of its positions of adjustment.

As illustrated, the carriage includes horizontally disposed carriage beams 7 mounted upon vertically disposed carriage guides 8, as indicated at 9. The lower ends of the guides 8 are connected by horizontal guides 10 which engage the inner faces of the uprights 1 in overlapping relations as will be clearly seen by reference to Fig. 1. The lower guides 10 are held in spaced relation from each other by a rod 11 which also functions as a treadle elevating rod for raising 70 the carriage upon actuation of the treadle, as will presently appear. Treadle bars 12 are shown pivoted on the rod 11, inside of the guides 10, washers 13 serving to hold the guides 10 in position. The carriage 75 members 7 are connected by transversely disposed bars 14 immediately beneath the carriage so that it will be seen that the carriage comprises a rigid structure slidable vertically on the uprights 1. The carriage structure, as a whole, also includes a truck 80 slidable on the carriage horizontally into lids supplying and lid applying positions.

As shown, the truck comprises a frame 85 consisting of longitudinal members 15 connected by transverse members 16, castors or rollers 17 being applied to the longitudinal members 15 to run upon tracts 18 which may comprise angle irons secured to carriage frame members 7. Upon the longitudinal 90 members 15 of the truck, I mount box guides 19, which may also be in the form of angle iron and which are provided with outwardly bent stop ends 20 and 21 for limiting movement of the truck in either direction. The 95 stops 20 and 21 abut against the frame uprights 1 and the latter may be faced with metal strips, as indicated at 22, to take up wear. On one end of the truck I mount a magazine which may comprise a base 23 on 100 which lids 24, are disposed, between corner holders 25. Lids of fruit boxes are usually in two parts and therefore I provide rods 26 for holding the stacks of lids in suitable spaced relation. The truck is of sufficient 105 length so that a box to be lidded may be slid on the guides 19 up against the magazine, when the truck is in a box receiving position as indicated in Fig. 3. Here it will be seen that the box 27 occupies a position outside 110 of the frame of the machine and this is the position which the truck will assume both

when the box is positioned to be lidded and after the lid has been applied and the box is to be removed.

I will next describe the manner in which 5 lids are transferred from the magazine so as to be applied to the boxes.

Lid suspending means is provided which consists of a pair of frames 27' both of which are pivotally mounted at 28 and 29 to 10 frame members 30, attached to the frame uprights 1 as indicated at 31. The frames 27' are shown rectangular in form and each is provided with an outermost bar 32 on which lids suspenders are disposed. The 15 particular form of lid suspender or holder, as shown in Fig. 7, comprises a pointed element 33 having a threaded portion 34, whereby they may be vertically adjusted, and each having a polygonal head 36 to 20 facilitate adjustment thereof. The frames 27' are pivoted so as to accommodate the central bulge which usually occurs when the ends of the lids are pressed down upon the 25 box and I reduce the extent of movement of the outer portions of the frames 27', with respect to their inner portions, by disposing the pivots 28 and 29 outwardly from the centers of the frames.

When the carriage and truck are in the 30 position shown in Figs. 1 and 3, the magazine is within transferring range, or in the present construction, in subjacent relation to the lid suspenders 33 so that when the carriage is elevated sufficiently to engage the 35 uppermost lids with the downwardly extending pointed suspenders 33, said uppermost lids will be held thereby in a suspended position as the magazine is lowered. The truck will then be shifted to dispose the box 40 beneath the suspended lids, as shown in Fig. 5 and the carriage will be elevated to abut the top of the box against the suspended lid or lids, and will be held in an elevated position until the lids are cleated into position 45 on the box. As the truck is shifted from a lid supplying to a lid applying position it is desirable to lock the truck against movement from either of said positions.

As shown, I mount upon the transverse 50 members 16 of the truck a locking bar 37 which is shown as being pivoted at 38 to one of said members 16. The other said members 16 is provided with a hanger 39 through which locking bar 37 extends and in which 55 it is afforded a limited up and down movement. The outer end of the handle bar 37 terminates in a hand grip 40 whereby the locking bar may be operated and the truck shifted from one position to another. The 60 locking bar 37 is provided with notches 41 and 42 adapted for engagement with a lock strip 43 mounted on and extending upwardly from one of the bars 14. The strip 43 and the bar 37 co-act with the stop ends 65 20 and 21 to positively lock the truck in

either of the two positions to which it may be adjusted, in the present form. When the truck is in a forward position, as shown in Fig. 3, then the stops 21 lock the truck against movement to the left, and notch 42 in bar 37, engaging strip 43, locks the truck against movement to the right of Fig. 3. The notch 41 serves a like purpose in locking the truck against movement to the right. 70

I will next describe the manner in which 75 the carriage is elevated to supply lids and thereafter apply the lids to the boxes.

On the outer ends of the treadle bars 12 I mount a tread 44 which is centrally slotted as indicated at 45. A transverse board 46 is 80 mounted on said bars 12, in spaced relation with respect to the tread 44, as shown more particularly in Fig. 9. The treadle is fulcrumed on the machine frame by strap hangers 47 which are pivoted at 48 to frame member 5 and at 49 to the treadle bars 12. The fulcrumed hangers permit of outward and inward movement of the treadle when the bar 11 travels upwardly and downwardly in a straight line of movement. 85 Thus when the treadle is depressed from the position shown in Fig. 1 to the position shown in Fig. 5, the straps or links 47 will be under tension and the free ends of the treadle bars 12 will transmit thrust to the 90 rod 11 to raise the carriage in the frame members 1. After the lids have been transferred from the magazine to the lid suspending devices and when the box has been elevated by the carriage into abutting relation with the suspended lid or lids, it is desirable to hold the box in the elevated position as 95 shown in Fig. 5, until the lid or lids have been cleated or nailed to the box body, and for this purpose, I provide a locking means 100 for locking the carriage in the position shown in Fig. 5 while the box is being nailed.

As illustrated, the locking device comprises a rod 50 which is pivotally mounted, as indicated at 51 to the frame of the machine. The rod 50 extends through an opening 52 in the other members of the friction locking device, which is indicated at 53. Said member 53 is pivoted at 54 to the tread 44, by means of angle irons 55 which span the tread 44 and the transverse support 46. The forward end of the locking member 53 is enlarged to provide a weighted end 56 whereby the member will normally assume an unlocking position. The rear of the member 53 extends upwardly to form a tread 57 whereby the member 53 may be rocked into the position shown in Fig. 5 to frictionally lock the member 53 on the rod 50 and hold the carriage in the elevated position shown in Fig. 5. The opening 52 is disposed in such angular relation with respect to the longitudinal axis of the rod 50 as to result in the requisite frictional grip 115 sufficiently to lock the machine in the position shown in Fig. 5. 120

tion shown in Fig. 5. The advantage of a frictional locking device will be apparent when it is realized that there is considerable variation even in boxes which are supposed 5 to be of a uniform stock size and therefore this form of lock will permit the box to be elevated in tight relation up against the suspended lids, irrespective of the difference in sizes and the amount of bulge of the lid 10 caused by the contents of the box so as to permit of tight engagement between the ends of the lids and the box body.

I provide the box 58 for cleats which are usually used in nailing lids, and it will be 15 seen by reference to Fig. 6 that there will be ample room to cleat the lids on the box from the top of the machine.

It is believed that the operation will be clear from the foregoing description, and 20 while I have herein shown and described one specific form of my invention, I do not wish to be limited thereto except for such limitations as the claims may import.

I claim:—

25 1. In a box lidding machine, a frame, lid holding means thereon, a box supporting truck movable into lid supplying and lid applying positions with respect to said holding means, a magazine for the lids carried by 30 said truck, means whereby said truck may be shifted to transfer a lid from said magazine to said holding means when said truck is in a supplying position and thereafter to shift said truck when in a lid applying position to abut the box against the lid held by said means, substantially as described.

2. In a box lidding machine, a frame, lid holding means thereon, a box supporting truck movable beneath said holding means 40 into lid supplying and lid applying positions, a magazine for the lids carried by said truck, and means for raising said truck to transfer a lid from said magazine to said holding means when said truck is in a supplying position and thereafter raise said truck when in a lid applying position to abut the box against the lid held by said means, substantially as described.

3. In a box lidding machine, a frame, a 50 lid holding means thereon, a box supporting truck slideable beneath said holding means into lid supplying and lid applying positions, mechanism for locking said truck in either position, and means for raising said truck to transfer a lid from said magazine to said means when said truck is in a supplying position and thereafter raise said truck when shifted to a lid applying position to abut the box against the lid held by said 55 means, substantially as described.

4. In a box lidding machine, a frame, lid holding means thereon, a box supporting truck movable into lid supplying and lid applying positions with respect to said holding 60 means, a magazine for the lids carried

by said truck, means whereby said truck may be shifted to transfer a lid from said magazine to said holding means when said truck is in a supplying position and thereafter shift said truck when in a lid applying position to abut the box against the lid held by said means, and mechanism for locking said last-named means to hold the box in abutting relation against the lid while the latter is nailed, substantially as 75 described.

5. In a box lidding machine, a frame, lid holding means thereon, a carriage slideable vertically on said frame toward said holding means, a box supporting truck including a lid magazine movable horizontally on said carriage into lid supplying and lid applying positions, and means for raising said carriage and truck toward said holding means when the truck is in a supplying position 80 and thereafter when the truck is in an applying position, substantially as described.

6. In a box lidding machine, a frame, pointed lid holding means on said frame, a box supporting mechanism including a device 90 for supplying lids, and means for shifting said mechanism to engage and transfer a lid from said device to said pointed means and thereafter engage the box against the lid held by said pointed means, substantially 95 as described.

7. In a box lidding machine, a frame, lid holding means thereon comprising rocking members provided with pointed elements, means for advancing a supply of lids against 100 said pointed elements to transfer the uppermost lid thereto and thereafter abutting a box against the lid held by said elements, substantially as described.

8. In a box lidding machine, a machine 105 frame, a carriage for supporting a box slideable on said frame in a straight path of travel, and mechanism for advancing said carriage toward a positioned lid comprising a treadle pivoted to said carriage and fulcrumed on said frame, substantially as described.

9. In a box lidding machine, a machine frame, a lid holder therefor, a box supporting carriage slideable on said frame in a 115 straight path of travel, mechanism for advancing said carriage and its box toward said lid holder comprising a treadle loosely suspended on said frame and pivoted to said carriage, and locking means comprising a member pivoted to the machine frame and a second member pivoted to the treadle and coacting with said first-named member, substantially as described.

10. A box lidding machine provided with 125 lid holding means comprising a rocking member provided with pointed lid holding elements located on one side of the rocking axis of said member for engagement with a lid near its nailing edge, that portion of the 130

member on the opposite side of such rocking axis lying in the path of the bulging portion of the lid for actuation thereby to rock said member in a direction to advance the 5 pointed elements toward the box to be lifted, substantially as described.

11. A box lidding machine provided with a lid holding means comprising a rocking member provided with pointed lid holding 10 elements located on one side of the rocking axis of the member for engagement with a lid near its nailing edge, that portion of the frame member on the other side of such rocking axis lying in the path of the bulging 15 portion of the lid for actuation thereby to rock said member in a direction to advance the point of the elements toward the box to be lidded, the rocking axis of said member being located or centered with respect to 20 one dimension of said member and nearer to the pointed element end of said member than the other end, substantially as described.

12. In a box lidding machine, a machine 25 frame, lid holding means thereon, means for advancing a filled box into abutting relation with a lid held by said means, and locking means for holding said box in abutting relation with said lid irrespective of variation of size and contents of the box, substantially as described.

13. In a box lidding machine, a machine frame, a lid holder therefor, a box supporting carriage slidable on said frame, mechanism for advancing said carriage and its 35 box toward said lid holder comprising a treadle loosely suspended on said frame and connected with said carriage, and means for locking said treadle when the box is in abutting relation against the lid, substantially as 40 described.

14. In a box lidding machine, a machine frame, a lid holder for said frame, a box supporting carriage slidable on said frame, and treadle mechanism connected with the 45 carriage and fulcrumed on said frame for advancing a box against a positioned lid, substantially as described.

In testimony that I claim the foregoing as my own, I hereby affix my signature in 50 the presence of two subscribing witnesses.

OSCAR D. GIBBS.
